SUPPORTER IN UNDERGARMENTS

Samuel Wald, New York, N. Y.

Application October 20, 1939, Serial No. 300,338

1 Claim. (Cl. 128—159)

This invention relates to new and useful improvements in a supporter in men's and women's undergarments.

More specifically, the invention proposes the provision of a substantially crescent shaped hollow pouch for location upon the crotch of undergarments to act as a supporter in this vicinity. When used upon men's under-wear it is proposed to act as a supporter for the male organs. When used on women's under-wear it is intended to support absorbent pads or similar material for use during menstruation periods.

Still further the invention proposes a specific construction of the pouch in which it is designed to be of one piece with the garment material.

Still further the invention proposes a modified form in which the pouch is arranged so that it may be stitched in position upon the crotch portion of the undergarment.

Still further the invention proposes another modified arrangement wherein cords or strings are utilized to removably hold the pouch in its position.

As another object of this invention it is proposed to provide a means for supporting the top of the pouch in an elevated position so as to satisfactorily hold it when in use.

For further comprehension of the invention, and of the objects and advantages thereof, reference will be had to the following description and accompanying drawing, and to the appended claim in which the various novel features of the invention are more particularly set forth.

In the accompanying drawing forming a material part of this disclosure—

Fig. 1 is a perspective view of a pair of men's trunks provided with a support in accordance with this invention.

Fig. 2 is a plan view of the trunks illustrated in Fig. 1.

Fig. 3 is a fragmentary enlarged vertical sectional view taken on the line 3—3 of Fig. 2.

Fig. 4 is a fragmentary vertical sectional view similar to Fig. 3 but illustrating a garment constructed according to a modification of this invention.

Fig. 5 is a plan view of Fig. 4.

Fig. 6 is a fragmentary vertical sectional view taken on the line 6—6 of Fig. 5 but illustrating the pouch per se.

Fig. 7 is a perspective view of a pair of women's panties with a supporter constructed according to this invention.

Fig. 8 is a fragmentary enlarged vertical sec-

tional view of the crotch portion of the panties shown in Fig. 7.

Fig. 9 is a fragmentary sectional view similar to Fig. 8 but showing a garment constructed according to a still further modified form of this invention.

Fig. 10 is a perspective view of a supporter similar to that shown in Fig. 9, but illustrating a still further modified form of the invention.

Fig. 11 is a vertical sectional view, taken on the line 11—11 of Fig. 10.

The supporter, in accordance with this invention, is shown applied to a pair of men's trunks 10. These trunks may be of any design and construction and are intended to generally illustrate a man's undergarment. A substantially crescent shaped hollow pouch 11 is located upon the crotch portion 10a of the undergarment 10. This pouch 11 is perforated at 11' and is formed from a continuation of the material forming the crotch (see Fig. 3). At the upper edge the pouch 11 is formed with a plurality of darts 12 which are secured in fixed positions by lines of stitches 13. These darts assist in forming the pouch.

The pouch 11 is formed from two half sections 11a and 11b which are secured together at their adjacent contacting edges by a line of stitches 16 or by cementing. A means is provided for supporting the top of the pouch in an elevated condition and this means includes a pair of straps 18 located at opposite sides of the pouch and secured at their bottom ends to the material of the top edge of the pouch or made integrally therewith. These straps are adapted to extend upwards and at their upper ends are provided with elements 18a adapted to be attached to portions of the trunks 10 which are located above the crotch 10a.

Specifically, the elements 18a in the particular form of the invention illustrated on the drawing, are provided with button holes 20. The trunks are shown formed with an open front, the edge portions of which may be secured together by the buttons 21 along one of the sides, engageable with button holes 22 along the other of the sides. It is intended to provide additional buttons 21' within the trunks adapted to be engaged through the button holes 20 of the upper ends of the straps 18 in a manner so that the straps 18 are supported and thus the pouch is held. Instead of buttons, snap fastener, or any other means may also be provided for detachably or permanently securing the elements 18 to the garment. In this particular form of the

invention, the pouch is intended as a support for the male organs.

In Figs. 4-6 inclusive, a modified form of the pouch has been disclosed which distinguishes from the prior form essentially in the fact that the pouch is made from material separate from the material of the trunks. Specifically, this form of the invention illustrates a pouch 11 formed from two sections of material 11^a and 11^b which are secured together by a line of stitches 16. These sections are fashioned with darts 12 so as to form the pouch into crescent shape.

The upper edges of the pouch are reinforced with rubber tubing material 14. This rubber material 14 is in the form of a tube disposed within a turned down edge portion of the pouch. A line of stitches 15 holds the turned down edge portion fixedly in position. At the bottom end, the pouch 11 is formed with extensions or tabs 24. These tabs are adapted to be folded so that portions are upon other portions thereof, as illustrated in Fig. 4, and then the folded tabs are secured to the material of the crotch by stitches 25. The tabs 24 comprise continuations from the edge portions of the sections 11^b and 11^a at the crotch area.

In other respects this form of the invention is similar to the previous form.

In Figs. 7 and 8, another modified form of the invention has been disclosed, which distinguishes from the prior forms in the fact that the supporter has been shown applied to ladies' panties. In this form of the invention the ladies' panties 30 have a crotch portion 30^a and a crescent shaped hollow pouch 31 is mounted upon and secured to the crotch portion. The pouch 31 is formed of cloth material. It is lined with a waterproof lining 32 which is of separate material, preferably of rubber, oiled silk, or other waterproof material, and is merely set into the pouch 31. An absorbent pad 33 is set into the water proof lining 32. This pad 33 preferably is constructed of sponge rubber. At the top it is provided with a small upwardly projecting central rib portion 33^a intended to engage in the extremity of the body cavity to assist in its operation of absorbing liquids.

The pouch 31 at its bottom portion is provided with tab elements 31^b which comprise merely continuations from the edge portions of sections used in making the pouch. These tabs 31^b are folded so that there are superimposed layers. Stitches 34 engage through the folded tabs 31^b and the material of the crotch 30^a to securely hold the pouch in position.

A means is provided for supporting the top of the pouch in an elevated position to properly hold it against the body. This means includes a pair of straps 35 attached at their bottom ends to the front and rear portions of the pouch 31. These straps are provided with fastening elements 36 at their upper ends adapted to be attached to the material of the panties 30 to hold the pouch in the supported position previously referred to.

In Fig. 9 another modified form is disclosed which distinguishes from the prior form in the

fact that a construction has been provided which permits the pouch to be removed. Specifically, the water proof lining 32 of the pouch has several strings 36 attached to the inner face of the bottom portion thereof. These strings pass up through openings 37 formed in the pad 33, and at their upper ends these strings 36 are formed with knots 36^a. These knots serve to hold the pad 33 in position within the lining 32 of the pouch.

Additional strings 38 are attached to the outer face of the water proof lining 32 of the pouch, in line with the strings 36. These strings 38 pass through openings 39 formed in the pouch 31. The strings 38 have tips 40 so that they may readily be laced through openings 41 formed in the material of the crotch 39. When the strings 38 are laced through the openings 41, they are then tied into a bow 38^a which serves to releasably hold the pouch on the crotch.

When desired the strings 38 may be untied, and then the pouch may be removed. Tension from the strings 38 in their tied positions, are transmitted to the strings 36 which in turn securely hold the pad 33 in position. This prevents accidental displacement of the parts.

In Figs. 10 and 11 the pouch 31 is illustrated with strings 38 for fastening the pouch to the crotch as shown in Fig. 9. The tab 24' projecting from one side of the pouch is provided for folding the same under the opening 31', at the bottom of the pouch 31. This tab prevents any dripping from the moist pad 33 while the garment is worn. Upon removal of the pouch 31, the pad 33 may be washed within the pouch and by squeezing the mouth of the pouch and also through the bottom opening 31'.

While I have illustrated and described the preferred embodiments of my invention, it is to be understood that I do not limit myself to the precise constructions herein disclosed and the right is reserved to all changes and modifications coming within the scope of the invention as defined in the appended claim.

Having thus described my invention, what I claim as new, and desire to secure by United States Letters Patent is:

In combination, an undergarment having a crotch with openings therethrough, a pouch formed of waterproof material, an absorbent pad, and means removably mounting said pad in said pouch and removably mounting said pouch in said crotch, comprising a pair of strings, means mounting one end of each of said strings on the inner surface of said pouch whereby the free ends of said strings may be tied around said pad, a second pair of strings, and means mounting one end of each of said second pair of strings on the outer surface of said pouch immediately opposite the first-mentioned means whereby the second pair of strings may be engaged through the openings in said crotch and tied, whereby to hold said crotch, said pad, and said pouch in substantially fixed relationship.

SAMUEL WALD.
